UNITED STATES PATENT OFFICE.

FRANK A. GOODFELLOW, OF ALTOONA, PENNSYLVANIA.

FORCED-FEED LUBRICATOR.

1,369,422.

Specification of Letters Patent. Patented Feb. 22, 1921.

Application filed August 3, 1920. Serial No. 400,950.

To all whom it may concern:

Be it known that I, FRANK A. GOODFELLOW, a citizen of the United States of America, and resident of Altoona, in the county 5 of Blair and State of Pennsylvania, have invented a certain new and useful Improvement in Forced-Feed Lubricators, of which the following is a true and exact description, reference being had to the accompanying drawings, which form a part thereof.

My invention relates to a forced feed lubricator and has for its object to provide a lubricating device which will give a practically continuous feed and flow of oil and in which the operative parts are so arranged in connection with an oil reservoir as to make them very accessible for inspection and repairs or replacements. A further advantageous feature which I have in view is to provide a practically straight passage for the oil from the reservoir through the pumps to the passage outlet of the pumps.

The nature of my improvements will be best understood as described in connection with the drawings in which they are illustrated and in which—

Figure 1 is an end view of a reservoir, feeding pumps and pump actuating mechanism attached externally to the sides thereof, the reservoir being shown in section on the broken line 1—1 of Fig. 2 and one of the pumps being shown in section on the line 2—2 of Fig. 2, and

Fig. 2 is a side elevation of the reservoir with the connected pumps and pump actuating mechanism.

A is the reservoir from the bottom of which leads a number of passages A', one only being shown in section, for the delivery of oil to the different pumps. A² is a chamber formed below the pump of the reservoir through which a heating fluid can be passed to heat the oil. A³ is a conduit through which the oil or sludge can be withdrawn from the reservoir. A⁴ is a hollow chamber extending from side to side of the reservoir through which passes an actuating shaft for the pumps. B is the cover plate of the reservoir, formed in which is an opening B' and an upwardly extending internally threaded flange B². C is a closing cap screwing into the threaded flange B² and preferably formed, as shown, with a high, dome-like opening so that after the oil expands it can find room for its increased bulk in the cup. D is a filter which is advantageously secured in the opening B', as shown. E, E, are bearings for the actuating shaft which is indicated at F. This shaft can be rotated by any suitable devices and I have not shown such actuating mechanism save that. At G there is indicated, though not shown in detail, the location of a brake ratchet which I have used to prevent reverse motion of the shaft in connection with other mechanism (not shown) for rotating the shaft. G' G' are cams, preferably eccentrics, secured to the shaft F on opposite sides of the reservoir. The shaft may be rotated by any convenient attachment, none being shown in the drawings. H, H', are plunger holding members secured to the bottom of the reservoir on each side, the portions H of these members having formed in them oil channels H² which register with the channels A' and having also formed in them passages H² the upper ends of which are threaded as indicated at H⁴. I carry the channels H² through the members H closing their ends with a screw plug H⁵, as shown, and by removing these plugs ready access is given to passages H², A', for cleaning and air or steam can be forced into the 85 passages H² and through the bottom plungers and valves to clean them out. I is a valve box situated in the passage H², as shown, and provided with a non-return valve preferably a double valve consisting 90 of the two valves I' and I². J, J, are plungers screwing into the threaded opening H⁴, as shown, and formed with a central perforation J'. K, K, are plunger holding members secured to the top of the reservoir on each side by means of their flanges, K'. These members K are formed with threaded perforations K² into which screw the downwardly extending plungers L which are made of one-half the area of the plungers J and longitudinally perforated as indicated at L'. M, M, are oil ducts connected with the tops of the plungers L; each pair of plungers J and L are located in alignment one above the other. N is a plate 105 or casting in which is formed a yoke N' having contact faces N² N² which operate in connection with an eccentric G'. Formed or secured to the plate N are the cylinder holding members N³ N³ which, as shown in 110 Fig. 1, have formed in them the cylindrical chambers, one indicated at N⁴ in the lower

end and the other one indicated at N^5 at about the middle of the member and separated from the chamber N^4 by a perforated partition N^7 and a third chamber N^6 which 5 may practically form a continuation of the chamber N^5 which extends to the top of the member. The ends of the members N^8 are externally threaded, as shown. O is a cylinder adapted to operate in connection 10 with the end of the plunger J , the cylinder being situated in the chamber N^4 and made tight by the packing P and the gland indicated at P' , P^2 . Q is a valve casing situated in the chamber N^5 and provided preferably with two non-return valves Q' and Q^2 . O' is a cylinder fitting on the end of the plunger L and held in the chamber N^6 by a packing and gland similar to that which holds the lower cylinder in position. 15 R , Fig. 2, is an oil cup and R' a duct leading from it to lubricate the yoke and eccentric.

In operation the cylinder holding members and the cylinders secured therein have 20 a reciprocating motion communicated to them by the eccentric on the shaft M , this motion being alined by the stationary pistons. During the upward movement of the cylinders oil passes through the ports A' , 25 H^2 and non-return valve I , through the perforation J' of the plunger J into the cylinder O . On the downward movement of the cylinder the oil is forced past the non-return valve or valves of the valve casing 30 Q into the cylinder O' and as this cylinder is of only half the area of the cylinder O one-half of the oil forced into it will pass through the perforations of the stationary 35 plunger L to the delivery conduit M and, when the cylinders again move upward, the 40 remainder of the oil in the cylinder O' or such part of it as may be provided for by the clearance given, is forced through the perforation in the plunger L so that a practically continuous and even flow of oil is 45 maintained through the double acting pump.

It will be obvious that all operative parts 50 of my structure are readily accessible for inspection, repair or replacement and for this purpose it allows of the convenient removal of the plungers which, as is the case with the plunger L in the construction illustrated, can be made removable in a direction away from their opposing plungers. It will 55 also be obvious that by my construction ducts through which the oil passes through the apparatus are straight away and as little as possible obstructed or complicated.

Having now described my invention, what 60 I claim as new and desire to secure by Letters Patent, is:

1. In combination with a lubricator reservoir two perforated pump plungers of different diameters secured one above the other 65 on the outside of the reservoir, reciprocating

cylinders fitting on the ends of the perforated plungers, a passage leading from the reservoir to the perforation in one of the plungers, a non-return valve in said passage, a passage connecting the cylinders, a non- 70 return valve in said passage and an oil duct connected to the perforation of the second plunger.

2. In combination with a lubricator reservoir two perforated pump plungers of different diameters detachably secured one above the other on the outside of the reservoir, reciprocating cylinders fitting on the ends of the perforated plungers, a passage leading from the reservoir to the perforation 80 in one of the plungers, a non-return valve in said passage, a passage connecting the cylinders, a non-return valve in said passage and an oil duct connected to the perforation of the second plunger. 85

3. In combination with a lubricator reservoir two perforated pump plungers of different diameters secured one above the other on the outside of the reservoir, reciprocating cylinders, fitting on the ends of the perforated plungers, a passage leading from the reservoir to the perforation in the larger plunger, a non-return valve in said passage, a passage connecting the cylinders, a non-return valve in said passage and an oil duct 90 connected to the perforation of the second plunger. 95

4. In combination with a lubricator reservoir two perforated pump plungers of different diameters secured one above the other on the outside of the reservoir, a reciprocating member, cylinders secured in said member and fitting on the ends of the plungers, a passage connecting the cylinders, a non-return valve in said passage, a passage connecting the reservoir with the perforation in the larger plunger and a non-return valve 100 in said passage. 105

5. In combination with a lubricator reservoir plunger holding members secured on the outside of the reservoir, detachable pump plungers of different diameters secured one above the other to said members and formed with perforations extending through them, one of said plungers being removable from 110 its holding member in a direction away from the other plunger, an oil duct having a non-return valve connecting the reservoir with the perforation of the larger plunger, reciprocating cylinders fitting on and guided by 115 the plunger ends and a passage with a non-return valve connecting said cylinders. 120

6. In combination with a lubricator reservoir, a rotatable shaft extending through the reservoir carrying cams on opposite outer sides of the reservoir, two pairs of perforated plungers detachably secured to the lower sides of the reservoir and extending upward on opposite sides of the shaft, two pairs of 125 perforated detachable plungers of smaller 130

diameter secured to the upper sides of the reservoir and extending downward in alignment with the larger plungers, two cylinder holding members having yokes with which the cams operate to reciprocate the members, cylinders held in said members fitting on and guided by the plunger ends,

oil passages leading from the reservoir to the bottom of the larger perforated plunger, a non-return valve in each said passage, passages connecting the cylinders located one above the other and non-return valves in said passages.

FRANK A. GOODFELLOW.
